(57) CLAIM

The ornamental design for a tailgate holder, as shown and described.

DESCRIPTION

FIG. 1 is a front, top, right side perspective view of the tailgate holder of the present invention;

FIG. 2 is a top plan view of the tailgate holder of FIG. 1; FIG. 3 is a bottom plan view of the tailgate holder of FIG. 1;

FIG. 4 is a front elevational view of the tailgate holder of FIG. 1;

FIG. 5 is a rear elevational view of the tailgate holder of FIG. 1;

FIG. 6 is a front, top, right side perspective view of a second embodiment of the tailgate holder of the present invention; FIG. 7 is a top plan view of the tailgate holder of FIG. 6; FIG. 8 is a bottom plan view of the tailgate holder of FIG. 6;

FIG. 9 is a front elevational view of the tailgate holder of FIG. 6; and,

FIG. 10 is a rear elevational view of the tailgate holder of FIG. 6.
